UNITED STATES PATENT OFFICE.

STANHOPE BOAL, OF PIQUA, OHIO.

DESIGN FOR A HEATER.

SPECIFICATION forming part of Design No. 31,833, dated November 14, 1899.

Application filed September 14, 1899. Serial No. 730,509. Term of patent 7 years.

To all whom it may concern:

Be it known that I, STANHOPE BOAL, a citizen of the United States, residing at Piqua, in the county of Miami and State of Ohio, have 5 invented and produced a new and original Design for a Heater, of which the following is a specification.

The figure is a perspective view of a heating-stove, showing my design.

10 A represents the leg-base.

B represents the shell-base, on which is mounted the plain shell forming the body of the heater and the front plate F, secured to the base and shell. This front plate is of swelling 15 oval form having scroll ornamentation placed thereon. F represents such ornamentation. H represents the convex cover, having the

scroll ornamentation a, extending from the periphery to the crown thereof.

The leading feature of my design is a stove 20 or heater having the front plate of the shell of oval form with the scroll ornamentation thereon, the plain shell, and the ornamented convex cover.

Having described my invention, I claim— 25

The design for a stove or heater as herein shown and described.

In testimony whereof I have hereunto set my hand.

STANHOPE BOAL.
